LINING GUIDE CAM FOR NECKTIE
SEWING MACHINESJoseph A. Neumair, Hollis, N. Y., assignor to
American Machine & Foundry Company, a cor-
poration of New Jersey

Application May 2, 1942, Serial No. 441,464

3 Claims. (Cl. 112—152)

This invention relates to sewing machines, more particularly to improvements in necktie sewing machines. In necktie sewing machines such as shown in the co-pending application of C. W. Johnson and J. A. Neumair, Serial No. 420,618, filed November 27, 1941, the necktie lining passes between a pair of spaced, cam-actuated guides which engage the margins thereof and maintain it in a position wherein its longitudinal center line coincides with the elongated horizontal needle upon which it is advanced lengthwise and thereby stitched to the necktie fabric. In the type of machine referred to there is provided an endless rotary pattern band or cam whose edges engage cam followers connected to the lining guides, whereby the lining guides are moved toward and away from each other to maintain them in engagement with the lining edges along portions of varying width, as the lining is advanced upon the needle. The pattern band or cam with which such machines were equipped consisted of two sections mounted upon a wheel and having their ends fastened to each other, so that rotation of said wheel caused displacement of the lining guides toward and away from each other. However this type of cam did not permit for adjustment to compensate for variations in the degree of taper of different shapes of linings.

One of the main objects of the invention is to provide improved mechanism for guiding the lining. For this purpose there is provided an improved cam which consists of six pieces of sheet metal or other suitable material. One of these pieces is a starting point piece which has two parallel edges of unequal length and is not adjustable, it being fastened to the rim of the wheel and operating to spread the lining guides apart sufficiently to permit the leading end of the lining to be inserted therebetween. The lining is inserted transversely through an L-shaped slot in the table in front of the feeding and stitch-forming mechanism. The lining guide adjacent the inner end of the slot is controlled from the cam follower engaging the shorter parallel edge, and the other lining guide which is adjacent the bend in the L-slot is controlled from a cam follower engaging the longer parallel edge of the starting piece and is displaced beyond the outer side of the slot to permit the lining to be inserted between the lining guides. Thus the outer lining guide will not be returned inwardly to a position wherein it would obstruct the insertion of the lining until after the other lining guide has been displaced inwardly to the position wherein the latter begins guiding the inner lining edge. Here-

5 tofore both lining guides were simultaneously displaced inwardly into the positions wherein they began guiding the lining edges, and in case of over-travel of the pattern band the outer lining guide would be in a position wherein it obstructed the insertion of the lining into the slot. Since the longer parallel edge of my starting piece maintains the outer lining guide out of obstructing position for a longer interval there 10 is less likelihood of the insertion of the lining being obstructed by the movement of the outer lining guide into obstructing position, as there will be more time in which to stop the machine before the stated obstruction of the insertion of the lining will result.

15 To the starting piece are adjustably connected two pieces which are pivotally mounted at their other ends on the rim of the wheel to permit spreading apart of these pieces in conformity with variations in the degree of taper of the leading ends of various shapes of linings. Accordingly it is a further object of the invention to provide adjustment of the pattern band to compensate variations in the degree of taper of the 20 leading end of various shapes of linings. Moreover the outer edges of these pieces are flared outwardly adjacent the starting piece to correspond to the flaring shape of the leading end of certain types of necktie linings, so that the lining guides will be maintained in engagement with the same.

25 The neck-band piece, which is overlapped by the ends of the pivotally mounted pieces just described, is of uniform width and fastened to the wheel rim; or this piece may be eliminated and the wheel rim used instead. Two run-off pieces connect the neck-band piece and the starting piece. The run-off pieces may be pivotally mounted at one end on the neck-band piece and 30 adjustably secured at their other ends to permit them to be spread apart to correspond to variations in the taper of the trailing end of various shapes of linings. The outer edges of the run-off pieces may also be flared outwardly adjacent the starting piece to cause outward displacement of the lining guides in conformity with the flaring shape of the trailing end of certain types of linings.

35 Moreover the run-off pieces have straight inner edges and may be reversed on the wheel so that their straight edges guide the cam-followers to displace the lining guides in conformity with the straight taper of the trailing end of certain types of linings. Similarly, the other two pieces have 40 straight inner edges and may be similarly re-

versed to guide the lining guides in conformity with straight taper of the leading end of certain types of linings. This reversible feature constitutes still another object of the invention.

Certain types of linings have a tapering or flaring leading end and a more or less straight trailing end, and it is a further feature of the invention to provide for guiding such types of lining by appropriate adjustment of the pivoted pieces on the wheel.

Furthermore the pivoted pieces may be adjusted to compensate for different degrees of taper between the leading and trailing ends of the lining at one or both edges of the lining.

In the accompanying drawings which form a part of this specification and in which like characters of reference indicate the same or like parts:

Fig. 1 is a side elevation of a necktie sewing machine equipped with the improved pattern band or cam;

Fig. 2 is an end elevation thereof;

Fig. 3 is a detail side elevation of the supporting wheel with the improved cam mounted thereon;

Fig. 4 is a development shown in plan view of the supporting wheel with the cam mounted thereon;

Fig. 5 is a development shown in side elevation of the supporting wheel with the cam mounted thereon;

Fig. 6 is a cross-section on the line 6—6 of Fig. 4;

Fig. 7 is a cross-section on the line 7—7 of Fig. 4;

Fig. 8 is a cross-section on the line 8—8 of Fig. 4; and

Fig. 9 is a developed plan view similar to Fig. 4, showing the cam pieces reversed to engage their outwardly flared edges with the cam followers.

Referring to Fig. 1, wherein the type of sewing machine disclosed in the above-mentioned co-pending application of C. W. Johnson and J. A. Neumair is shown equipped with the improved pattern-band, the crimpler bars 10 on the upper sprocket chain 12 and the crimpler bars 14 on the lower sprocket chain 16 have suitably beveled faces to provide triangular teeth which inter-engage with each other as shown, to form pleats in the superposed necktie lining and fabric and advance the same over the eye 18 of the needle 20. The needle is slidably mounted in a needle holder 22 of well known construction arranged at the rear end of the machine. The shank of the needle extends forwardly from the needle holder and through transverse slots 24 and 26 in the crimpler bars 10 and 14 (Fig. 2). The slots of opposed crimpler bars are aligned with each other and coact to grip the needle while the superposed necktie lining and fabric are being advanced upon the shank of the needle, when the sprocket chains 12 and 16 are driven in a direction to stitch the lining and fabric together. Thus the needle is slid backwardly in its holder until its eye assumes the dotted position 18 shown in Fig. 1.

The opposed crimpler bars 28 and 30 have inter-engaging teeth which form a series of relatively narrow pleats in the leading end of the lining, so that upon penetration of the same by the needle there will be formed a series of short stitches ahead of the stitches formed when the pleats resulting from the inter-engagement of bars 10 and 14 are penetrated by the needle. There is also provided a crimpler bar 32 on the upper chain 12 which engages with one beveled face of an underlying crimpler bar 34, which is

10 of the same configuration and size as the bars 10 and 14 and mounted on the lower chain 16, to form a single pleat in both the lining and the leading end of the fabric thus uniting the same with a single short stitch when crimpler bars 32 and 34 advance this pleat in the lining and the underlying leading end of the necktie fabric on the needle. The opposed crimpler bars ahead of the bars 28 and 30 have the same configuration 15 and are mounted on sprocket chains 12 and 16 in the same manner as the crimpler bars 10 and 14 following the crimpler bars 32 and 34, and are accordingly designated as 10 and 14, respectively. The crimpler bars 28, 30, 32 and 34 have transverse slots similar to the slots 24 and 26.

15 The thread T is drawn from the spool S and guided through a ring 40 and through a hole in the bracket 42, the ring serving to tension the thread which is then drawn through a hole 44 20 in guide 46 and through a hole in an upright bracket 48 fastened to the needle holder, the thread being then drawn along the transverse slots of the crimpler bars wherein the needle is positioned and threaded through the eye 18 thereof. The lower sprocket chain 16 is formed as a triple width chain running over a triple sprocket 52 fastened on a shaft 52 supported in the front frame 54 (Fig. 1) and a rear frame 56 (Fig. 2), these frames being supported by a bed 57. Chain 16 25 also runs over a triple sprocket 58 mounted on a shaft 60 which is supported in the front and rear frames 54 and 56. Shaft 60 carries a sprocket 62 driven by a sprocket chain 64 from suitable reversing mechanism such as shown in the above mentioned application of C. W. Johnson, et al., Serial No. 420,618.

30 The reversing mechanism (not shown) may be operated as fully described in the above mentioned application to drive the shaft 60 forwardly or rearwardly, and a gear 110 mounted on shaft 60 will drive a gear 112 loosely mounted on a bolt 113 passing through the front frame 54 and supporting the rear end of the bars 114 and 115. A triple sprocket 116 loosely mounted on the portion of bolt 113 between the bars 114 and 115 drives the triple sprocket chain 12, the latter running over the triple idler sprocket 118 loosely mounted on the stud 120 (Fig. 1), threaded into the front end of the bar 114 which is fastened to the front frame 54 by a screw 121 passing through an elongated slot in the frame 54 (Fig. 2). The bolt 113 and the stud 120 are also connected by the support bar 115. On the stud 120 are loosely mounted rollers (not shown) at either end of the triple sprocket 118 to support the ends of the crimpler bars as they pass around the sprocket 118. A nut 122 threaded on the outer end of the shaft 120 retains the sprocket and rollers thereon. To the upper edge of the bar 114 is fastened a cover 202a overlying the upper run of the upper sprocket chain 12, and at the front end of the cover 202 is hinged a guard 204 which hangs down in position to prevent the operator from inserting her fingers between the upper and lower crimpler bars.

65 On the end of the shaft 52 protruding from frame 54 is mounted a pinion 130 which drives a ring gear 132 attached to a wheel 134 fastened on the shaft 136. The wheel 134 on its periphery carries the pattern band or cam 138 which forms the subject matter of the present invention and controls the cam followers of the lining guide mechanism. One of the cam followers 140 is supported by a block 142 fastened to a rod 144 which carries a block 146 to which is secured a guide finger 148 which has a downward-

ly bent portion on its upper end underlying the transverse portion 150 of the L-slot 151 in the inclined plate or table 152. The other cam follower 153 is carried by the block 155 which is fastened to a rod 157 passing through a notch in upper end of the block 146 and fastened to the block 159 on which is secured a guide finger 161, which is of the same shape as finger 148 and interchangeable with it, and also provided with a bent portion on its upper end underlying the transverse portion 150 of slot 151. Tension spring 163 is anchored to a hook 165 on block 159 and secured to a post 167 secured to the block 146. Thus the guide fingers 161 and 148 are yieldingly urged toward each other, the extent of separation thereof being determined by the contour of the cam 138 suitably designed to initially displace the finger 161 outwardly to a position wherein its bent upper end lies at the outer side of the bend in the slot 151 to permit the lining to be slid through the outer end of the slot into the transverse portion 150 thereof when the crimper bars 28 and 30 are approaching the position shown in Fig. 1 around the sprockets 118 and 50. At the same time the finger 148 is disposed in a position to engage one edge of a lining held centrally with respect to the notches 24 and 26 in the crimper bars and the needle. The leading end of the lining is then inserted between the crimper bar 28 and the preceding crimper bar 10, wherefore it is clamped between the adjacent sides of the same to be impaled upon the point of the needle as bars 28 and 10 are advanced to the position shown in Fig. 1. The leading end of the necktie fabric is superposed on the lining and inserted between the crimper bar 32 and the crimper bar 28, one edge of the fabric being positioned along a stationary guide (not shown) to place the fabric in the desired central position relative to the needle, the leading end of the fabric being clamped between the adjacent sides of the bars 28 and 32 and stitched to the lining as the bars 28 and 32 continue traveling toward the rear sprockets.

The length of the opposed runs of the sprocket chain is sufficient to stitch a desired maximum length of fabric to a lining, and the contour of the cam or pattern band 138 is such that the followers 148 and 161 are simultaneously displaced to predetermined positions at either side of the desired center line of the lining coinciding with the needle to properly guide the lining during substantially its entire length until the cam 138 returns to the position shown in Fig. 2 which occurs when the crimper bars 28 and 30 have been advanced a predetermined maximum distance toward their rear sprockets. The gear ratio between the ring gear 132 and the pinion 130 is such that when the sprocket chains 12 and 16 make one or more complete circuits around the sprockets and back to initial position the cam 138 will also be returned to its initial position.

The pattern band 136 selected to exemplify the invention consists of six cam pieces which are fastened to the periphery of the wheel 134. The starting piece 200 has parallel edges 201 and 202 of unequal length which engage the cam followers 140 and 153 respectively, at the initial position of the pattern band and thereby displace the lining guide 148 to a position adjacent the inner end of the slot portion 150 and displace the lining guide 161 to a position at the outer side of the bend in the slot 151 where it will not obstruct the insertion of the leading end of the lining into the guiding portion 150 of the

slot. As the cam follower 140 rides off the edge 201 on to the cam piece 204 the lining guide 148 is displaced into a position corresponding to the point of slot 150 at which the inner edge of the inserted lining should be disposed in order that its longitudinal center line should coincide with the needle. Subsequently the cam follower 153 rides off edge 202 and on to the cam piece 206, whereupon lining guide 161 is displaced inwardly to a position where it will engage the outer edge of the centered lining. The length of the cam pieces 204 and 206 corresponds to the length of the portion of the leading end of the lining to be guided.

15 As shown in Figs. 2, 4 and 8, the cap screw 208 is threaded into the wheel and passes through a hole in the starting piece 200 and elongated slots 209 in the underlying ends of the cam pieces 204 and 206, to secure the same to the rim of wheel 134. The outer sides of cam pieces 204 and 206 have straight edges extending from the starting piece to their outer ends, and the cam followers ride upon these edges until they engage the neck band piece 211. The cam pieces 204 and 206 and the underlying portion of the neck band piece are secured to the rim of wheel 134 by cap screws 213 and 215 threaded into the wheel, the screw 213 passing through elongated slots 217 and a hole in the neck band piece and the screw 215 passing through aligned holes in the pieces 204 and 206 and the neck band piece.

20 When the neck band piece travels past the cam followers, they engage the straight outer edges of the run-off pieces 220, which have a length corresponding to the portion of the trailing end of lining to be guided, and are secured to the neck band piece by a cap screw 223 threaded into the rim of the wheel. At their other ends the pieces 220 are secured to the starting 25 piece by a cap screw 221 threaded into the wheel and passing through elongated slots 222 in these pieces and a hole in the starting piece. A cap screw 224 passing through elongated slots 226 in the pieces 220 is threaded into the wheel and 30 secures the middle portion of these pieces thereon. After the run-off pieces are moved past the cam followers the latter re-engage the starting piece, and the machine is reversed by depressing the other end of treadle 104, whereby the pattern band is returned to the initial position 35 shown in Fig. 2.

40 The neck band piece is of substantially uniform width in conformity with the uniform width of the neck band part of most shapes of necktie linings, but the degree of taper of the leading and trailing ends of various shapes of necktie linings may vary. Hence, upon unloosening the screws securing the pieces 204, 206 and 220 to the wheel they may be spread apart or brought closer together, the screws 215 and 223 respectively serving as pivots. As shown in Fig. 4, the cam pieces 204 and 206 have been adjusted for a degree of taper of the leading end of the lining which is greater than the degree of taper of its trailing end, as indicated by the dimension lines A and B, respectively. However, either of the pieces 204, 206 or either of pieces 220 may be adjusted so that it will be asymmetrically arranged with respect to the other piece of its pair, in conformity with any desired condition.

45 It will be noted that the outer ends of the slots 222 extend into the proximity of the outwardly flared edges of the pieces 220, so that the pieces 220 in Fig. 4 may be spread apart until the inner 50 ends of slots 222 adjacent the edges of the out-

wardly flared portions of these pieces engage the screws 221. Thus the pieces 220 may be spread apart to a greater extent than if the inner ends of the slots 222 terminated at a point aligned with the continuation of the straight edges of the pieces 220 extending from said outwardly flared edges.

The cam pieces 204, 206 may be reversed on the wheel, as shown in Fig. 9, so that the edges 230 thereof, which are flared outwardly adjacent the starting piece in conformity with the flared contour of the corresponding portion of the leading end of another type of lining, will displace the lining guides to maintain them in engagement with the edges of the leading end of the type of lining referred to.

Some types of linings have a trailing end of substantially uniform width, and to compensate for the same the run-off pieces 220 may be arranged as shown in Fig. 9. In this case the outwardly flared portions of the pieces overlap the starting piece 200 so that the outer edges of the pieces 220 define a continuation of the neck band piece up to the starting piece. This arrangement of the pieces 220 may be used in conjunction with the arrangement of the pieces 204 and 206 shown in Fig. 9, for guiding a lining having a flared leading end and a trailing end of uniform width.

What is claimed is:

1. In a necktie sewing machine having a stitching position, the combination with a guide member engaging and guiding a necktie part as it is fed to said stitching position to maintain a predetermined relation between the edges of the necktie part and said position, of a cam follower connected to said member, a support rotating upon a horizontal axis, and a series of cam pieces mounted on the periphery of said support in position to successively engage said follower and thereby displace said follower to different positions, a plurality of said cam pieces being pivotally mounted at one end thereof and individually adjustable upon their pivots transversely of said support to vary the displacement of said guide member in accordance with the requirements of different shapes of necktie parts.

2. In a necktie sewing machine, the combination with a support rotating upon a horizontal axis, of a pair of cam pieces mounted on said support, a pair of lining guide members ar-

ranged to engage the edges of a necktie lining and guide the same as it is advanced lengthwise therebetween, a pair of cam followers connected to said members and arranged to engage the lateral edges of said cam pieces, yielding means urging said followers against said cam pieces, the contour of said lateral edges of the cam pieces being such that members will be displaced toward each other to follow the contour of the tapered leading end of a lining advanced therebetween, said cam pieces being pivotally mounted at their ends upon said support and individually adjustable thereon about their pivots to vary the displacement of said members to follow the contour of edges of the leading ends of linings having different degrees of taper.

3. In a necktie sewing machine, the combination with a support rotating on a horizontal axis, of a starting cam piece mounted on said support, a neckband cam piece mounted on said support, a pair of primary cam pieces mounted on said support and connecting said starting and neckband cam pieces, a pair of lining guide members arranged to engage the edges of a necktie lining and guide the same as it is advanced lengthwise therebetween, cam followers connected to said members and arranged to engage the lateral edges of said primary cam pieces for displacement of said members toward each other to follow the contour of the tapered leading end of a necktie lining, a second pair of tapered cam pieces mounted on said support and connecting said neckband piece and starting piece and having straight lateral edges on one side and outwardly flared lateral edges on the other sides adjacent the rear ends thereof, the second pair of cam pieces being pivotally mounted on said neckband piece at their forward ends and adjustable transversely upon their pivots and having their straight lateral edges arranged to engage the followers after the latter leave the neckband piece, said secondary cam pieces having aligned transverse slots extending into the outward flared portions thereof, a screw passing through said slots and threaded into said support whereby the secondary cam pieces may be adjusted outwardly on their pivots until the inner ends of said slots engage said screw, and a means for yieldingly maintaining said followers in engagement with the edges of said cam pieces.

JOSEPH A. NEUMAIR.
